US0D1002438S

(12) **United States Design Patent** (10) **Patent No.:** **US D1,002,438 S**
(45) **Date of Patent:** **** Oct. 24, 2023**

(54) **MOTORCYCLE**

(71) Applicant: **Burromax LLC**, Kirkwood, MO (US)

(72) Inventor: **Kenneth A. Francis**, Kirkwood, MO (US)

(73) Assignee: **Burromax LLC**, Kirkwood, MO (US)

(**) Term: **15 Years**

(21) Appl. No.: **29/807,045**

(22) Filed: **Sep. 8, 2021**

(51) LOC (14) Cl. **12-11**

(52) U.S. Cl.

USPC **D12/110**

(58) **Field of Classification Search**

USPC D12/110, 111, 117; D21/432, 538

CPC B62K 11/00; B62K 11/02; B62K 11/04; B62K 11/10; B62K 17/00; B62K 19/00;

B62K 2202/00
